DUMP SCOW

Robert H. Miller, 1404 Arden Lane, Manitowoc, Wis.

Filed May 6, 1964, Ser. No. 79,836

Term of patent 14 years

(Cl. D71—1)

FIG.1

FIG.2

Des. 201,407

PAGE 2

FIG. 3

FIG. 4

FIG. 5

FIGURE 1 is a side elevational view of a dump scow showing my new design;

FIGURE 2 is a plan view thereof;

FIGURE 3 is a bottom view thereof;

FIGURE 4 is a front elevational view thereof;

FIGURE 5 is a rear elevational view thereof, and

FIGURE 6 is a perspective view taken from the rear illustrating the dump scow in a dumping condition.

The side not shown is substantially the same as the side illustrated.

I claim:

The ornamental design for a dump scow, substantially as shown and described.
